FIG. 2.

Inventor:
E. E. Neal.
By his attorney,
Harold S. Gooding.

UNITED STATES PATENT OFFICE.

ENOCH E. NEAL, OF MELDEN, MASSACHUSETTS.

VENTILATING APPARATUS FOR TOILET BOWLS.

Application filed February 18, 1927. Serial No. 169,367.

This invention relates to a ventilating apparatus for toilet bowls and particularly to a mechanism for controlling the operation of said apparatus.

The object of the invention is to provide a toilet bowl with a ventilating apparatus so associated therewith that if said bowl becomes clogged and the water therein rises above its usual level when the bowl is flushed 10 that said water will not interfere with or submerge said apparatus.

Another object of the invention is to provide a novel mechanism for operating a switch that controls the operation of the 15 electric motor which drives the suction pump, said mechanism operating automatically to close the electric circuit to said motor when the seat is depressed, and also to open said circuit when pressure upon said 20 seat is withdrawn.

The invention consists in a ventilating apparatus for toilet bowls as set forth in the following specification and particularly as 25 pointed out in the claims thereof.

Referring to the drawings:—

Figure 1 is a side elevation of a toilet bowl, a ventilating apparatus embodying my invention being illustrated associated therewith.

Fig. 2 is a plan view of a portion of the apparatus illustrated in Fig. 1, a portion 30 of the cover for the toilet bowl being broken away to more clearly illustrate parts located therebeneath.

Fig. 3 is a detail vertical section taken on the line 3—3 of Fig. 2, the cover for the bowl being raised and the seat being illustrated in its depressed position.

Like numerals refer to like parts throughout the several views of the drawings.

In the drawings, 5 represents a toilet bowl of well-known form, 6 a seat, and 7 a cover located above said seat. The seat 6 has a cushion 8 attached to the undersurface thereof and so positioned relatively to the top edge of said bowl that when said seat is depressed said cushion will tightly close any space that there may be between said seat and said bowl.

Rigidly fastened to the top surface of the bowl 5, adjacent to the rear thereof, are a pair of similar brackets 9 in which a rod 10 is mounted, and the latter constitutes a pivot for the cover 7 which is connected to said rod by a pair of arms 11. The cover 7 has

a cushion 12 secured to its undersurface at the front thereof, and said cushion rests upon the front portion of the seat 6. Pivotedly mounted upon the rod 10 between the arms 11 of the cover 7 is a rocker member 13, 60 and the latter has a pair of forwardly projecting arms 14 formed integral therewith in which the rod 15 is mounted.

A plate 16 is secured to the undersurface of the seat 6 adjacent to the rear thereof, and said plate has a pair of rearwardly projecting arms 17 formed integral therewith, which are pivotally mounted upon the rod 15. The rod 15, therefore, constitutes a pivot 65 for the seat 6 and in its normal position said seat at the rear thereof is raised, so that its cushion 8 is out of engagement with the top edge of the bowl 5, except at the very front of said bowl.

A forked member 18 is connected to the opposite extremity of the rocker 13 from that to which the seat 6 is pivoted, and said forked member is connected by a weighted connecting rod 19 to a switch 20 hereinafter to be more fully described. The connecting 70 rod 19 constitutes a weight and is sufficiently heavy to normally hold the seat 6 in the raised position illustrated in Fig. 1.

Resting upon the upper surface of the toilet bowl 5 at the rear thereof, with its entrance positioned adjacent to the rear of the seat 6, is a suction nozzle 21, and said nozzle is connected by a vent pipe 22 with a suction pump 23 driven by an electric motor 24. A discharge pipe 25 leads from the 75 suction pump 23 to any suitable location, but preferably said pipe discharges into the open air.

The switch mechanism 20, previously mentioned, embodies therein a pair of electric 80 contact members 26 and 27, both of which are mounted upon an insulating block 28 mounted within a casing 29. The contact member 26 is connected by a wire 30 with the electric motor 24. The contact member 27 is connected by a wire 31 with a suitable 85 source of electric supply 32 and the latter is connected by a wire 33 with the motor 24. The weighted connecting rod 19 is operatively connected with a lever 34 pivotally 90 mounted at 35 within the casing 29, and said lever has a push member 36 constructed of insulating material fast thereto and adapted to engage the contact member 26 95 when said lever is rocked, thereby forcing 100 105 110

said contact member into engagement with the contact member 27, and completing the electric circuit through said members.

Whenever the seat 6 is depressed, which happens whenever a person is seated thereon, the member 13 is rocked upon its pivot 10, thereby operating the lever 34 to complete the electric circuit at the switch 20 to the motor 24, and the immediate operation 10 of the suction pump 23 causes the suction created to discharge the fumes from the toilet bowl.

As soon as the pressure upon the seat 6 is removed, the weighted member 19 will immediately cause the seat 6 to return to its normal position as illustrated in Fig. 1, at which time the electric circuit at the switch 20 will be broken.

The cover 7 is so mounted upon the pivot 20 10 and rests in such a manner upon the front of the seat 6 that any pressure downwardly thereon, as by a person sitting upon said cover, will not have any effect upon the seat 6 other than to slightly compress 25 the cushion 8 at the front of said seat.

It is evident that all of the mechanism hereinbefore described is so arranged with relation to the toilet bowl that if the latter in any way becomes clogged, so that in flushing 30 the toilet the water therein rises above its accustomed level, that none of the parts of this mechanism will be submerged.

It is furthermore evident that as there is no switch or electric wires either upon the 35 seat or adjacent to the top of the toilet bowl that there will be no danger in the device of this invention of water splashing within the bowl causing short circuits in the electric switch or wires connecting thereto.

40 I claim:—

1. In combination a toilet bowl, a vent pipe communicating therewith, a suction pump connected to said pipe, an electric motor for said pump, a switch for said motor, a seat for said bowl, and a weight 45 rigidly connecting said seat and said switch, whereby the latter is operated by said seat to control the operation of said motor.

2. In combination a toilet bowl, a vent pipe communicating therewith, a suction 50 pump connected to said pipe, an electric motor for said pump, a switch for said motor, a seat for said bowl, and means operatively connecting said seat with said switch, whereby the latter is operated in 55 unison with said seat to control the operation of said motor, said means embodying therein a weight comprising a rigid connecting member and adapted to hold said seat in its normal position. 60

3. In combination, a toilet bowl, a vent pipe communicating therewith, a suction pump connected to said pipe, an electric motor for said pump, a switch for said motor, a rocker pivotally mounted upon 65 said bowl, a seat for said bowl pivotally attached to said rocker, and a weight connected to said rocker and adapted to hold said seat in a raised position, said weight also being operatively connected to said 70 switch, and comprising a rigid connection between said rocker and switch, whereby the latter is operated in unison with said seat to control the operation of said motor.

4. In combination, a toilet bowl, a vent 75 pipe communicating therewith, a suction pump connected to said pipe, an electric motor for said pump, a switch for said motor, a pair of brackets mounted upon said bowl, a pivot member in said brackets, a rocker mounted upon said pivot members, a seat for said bowl pivotally attached to said rocker, a weight connected to said rocker and adapted to hold said seat in a raised position, said weight also being operatively 85 connected to said switch and comprising a rigid connection between said rocker and switch, whereby the latter is operated in unison with said seat to control the operation of said motor, and a cover for said 90 bowl also pivotally mounted upon said pivot members.

In testimony whereof I have hereunto set my hand.

ENOCH E. NEAL.
